UNITED STATES PATENT OFFICE.

THOMAS H. WADDEN, OF KEOKUK, IOWA.

VEHICLE DISPLAY DEVICE.

1,214,621.

Specification of Letters Patent.

Patented Feb. 6, 1917.

Application filed November 6, 1913. Serial No. 799,544.

To all whom it may concern:

Be it known that I, THOMAS H. WADDEN, a citizen of the United States, residing at Keokuk, in the county of Lee and State of 5 Iowa, have invented certain new and useful Improvements in Vehicle Display Devices, of which the following is a specification.

This invention relates to devices such as are used for displaying identification numbers 10 of vehicles such as automobiles, by use of the rays of light from the tail lamp.

It is one of the features of my invention to provide a casing structure for direct attachment to the bull's-eye holder of an ordinary 15 bicycle or vehicle lamp so as to secure the benefit of the greatest illumination of the number plate or matter to be displayed.

A further feature consists in providing a flat reflector which is disposed at such an 20 angle with respect to the display plate, and with respect to the projection of rays of light from the source thereof, that all of the reflected rays will be oblique to or will travel in lines oblique to the surface of the reflector 25 thereby increasing the intensity of the light rays reflected upon the display plate.

A further feature resides in the novel form of mounting for the reflector plate within the display casing, and to means for 30 fastening the reflector plate and a backing therefor when the casing is closed.

Other features and novel objects of the invention will be more fully described in connection with the accompanying drawing and 35 will be more particularly pointed out and ascertained in and by the appended claims.

In the drawing: Figure 1 is a view in side elevation of a display device embodying one 40 form of my invention. Fig. 2 is a sectional view on line 2—2 of Fig. 1. Fig. 3 is a sectional view on line 3—3 of Fig. 2. Fig. 4 is a sectional view on line 4—4 of Fig. 1.

Like characters of reference designate 45 similar parts throughout the different figures of the drawing.

As illustrated, 1 designates the body of a lamp such as is used upon bicycles and vehicles and which is provided with a mounting means such as a hook 2. The body 1 is 50 provided with the usual bull's-eye holder which consists of a flared extension 3 in which a bull's-eye, indicated in dotted lines at 3', may be mounted. A tapered substan-

tially cylindrical portion 4 is receivable in the flared extension 3, and secured by clips 55 4', from whence it is shaped to form a substantially rectangular inclosure comprising a back wall 5, a bottom wall 4, a top wall 6 and a front wall 7. The clips 4' do not enter into my present invention, but are merely 60 illustrative of one manner of connecting the lamp with the casing. The casing comprises a substantially elongated or tubular extension of the bull's-eye holder which is provided with an open end. The wall 7 of 65 the casing is open at a point laterally of the projection of the light rays from the lamp 1 and the marginal portions of the open front wall are bent, as indicated at 9, to form top and bottom guide ways for a display plate.

The display plate is indicated at 10 and may be composed of translucent material in which transparencies are provided in the form of the subject matter to be displayed, 75 such as indicated at 11. The guides 9 will be formed to somewhat firmly grip the display plate 10 so that when the same is slid endwise across and in front of the open front wall 8, it will be held in place by friction. The outer end of the casing is open 80 and the edges of the back and front walls, 5 and 7, are bent to form guide ways 12 and 13, which are shown extending vertically of the casing to accommodate an end cover 85 plate 14, for closing the said open end of the casing. The guide way 13 forms an abutment for the ends of the display plate, indicated at 15, so as to prevent movement 90 of the display plate beyond a predetermined position.

A light reflector is provided in the form of a flat plate 16 which will preferably have a polished mirrored reflecting surface and which will have an area at least sufficient to 95 include in the rays reflected therefrom the area occupied by plate 10 carrying the subject matter to be displayed, such as the numerals 11. I have devised novel means of mounting the reflector plate, which I will 100 now describe in detail.

A backing 17 is provided which is preferably equal in area with the area of the reflector plate 16 and which is disposed rearwardly thereof to support the same. The 105 height of the plate will preferably be sub-

stantially equal to the height of the casing, as indicated in Fig. 3, and the plate 16 will be disposed in angular relation with respect to the longitudinal axis of the casing so that its one or inner end 18 will lie adjacent the back wall 5. I provide abutments, preferably flanged as indicated at 19, for engaging the end edge 18 of the plate 16 and the corresponding end edge of the backing plate 17. The opposite end edge 20, abuts against the front wall 7 of the casing, laterally of the opening 8 therein. The backing plate 17 is provided with a forwardly turned edge margin 21 which extends forwardly of the reflector plate 20 into the guide way 13. The guide way 13 is sufficiently enlarged so as to take the retaining forwardly bent flange or edge 21 and also the forward edge 22 of the end cover plate 14. It will thus be seen that when the end cover plate 14 is in place, it will lock both the backing plate and the reflector plate against displacement at both end edges of both plates. The angular disposition of said plates is such that when the cover plate 14 is in a closed position the guide way 13 and the cover plate at one end will so coact with the abutments 19 at the other end of said plate that the plates will be fixed in position.

80 The rays of light coming from the source of light, are indicated at 23. The rays of light reflected from the plate 16, are indicated at 24. It will be seen that the angle of reflection is uniformly the same throughout the reflecting field of the plate 16. I have found that by having a flat reflecting plate 16 disposed in such relation with respect to the line of projection of the light rays from their source, or in other words, at 40 such an angle to the angle of radiation of light, that I very appreciably and materially reduce refraction and cause such dissemination of the light with respect to the translucent slide or display plate 10, as to most effectively illuminate the transparent portions thereof.

As is well known, the intensity of light rays is reduced in proportion to the length of travel thereof, which fact is especially noticeable in a source of light of the ordinary character. Now the primary rays from the source at *a*, for instance, would travel an appreciably decreased distance with respect to the primary rays striking the plate 16 at *c*, thus the reflected rays of incidence, such as at *b*, would have a greater intensity than those at *c*. However, the intensity of the primary rays at *e*, passing through the reflected rays, will be somewhat lessened by the time they reach or fall upon the reflector 16 at *c*. It will therefore be seen that I equalize the intensity of the rays of incidence throughout the area of reflection so that there will be a diffusion or supply of light upon the slide or display plate 10 of

such substantial uniformity as to illuminate the numerals "1913" as effectively as the numeral 2 would be illuminated.

While I have herein shown and described one specific form of my invention I do not 70 wish to be limited thereto except for such limitations as the claims may import.

I claim:—

1. In a vehicle display device, the combination with a lamp having a light concentrating and projecting means associated therewith, a casing to receive longitudinal projection of the light rays therethrough from said lamp and having the outer end thereof open, said casing having a wall open 75 at a point laterally of the projection of the rays from said lamp, a display plate for closing said opening, a reflector plate in said casing, a backing member for supporting the reflecting plate, an abutment for holding the backing member and reflecting plate at one point in the casing, and a cover plate for the outer open end of said casing 80 engaging said backing member to anchor the same at another point in said casing. 90

2. In a vehicle display device, the combination with a lamp structure, of a rectangular casing extending therefrom to receive projection of the light rays longitudinally therein, said casing having a display opening, a display plate spanning said opening, a reflecting plate in said casing, a backing member for supporting said reflecting plate, an abutment for engaging the reflecting plate and backing member to hold the 100 same against movement in said casing in one direction, said casing having an open end, and a cover plate for the open end engaging said backing member to hold the reflecting plate against said abutment and 105 against movement in another direction.

3. In a vehicle display device, a rectangular elongated casing having an open end and closure guides at the open end thereof, means for projecting light into said casing, a display plate for said casing, a reflecting plate obliquely arranged in the casing, a backing plate for supporting said reflecting plate, abutments for engaging the ends of said backing plate and said reflecting plate 110 at one end of the casing, one portion of said backing plate being flanged to engage one of the closure guides at the open end of said casing, and a cover plate slidable in the guides of the open end of said casing engageable with said flange to cause the backing plate to hold the reflecting plate in engagement with one wall of said casing and against displacement therein, said reflecting plate being adapted to reflect light to the 115 display matter, substantially as described. 120

4. In a vehicle display device, the combination with light projecting means, of a casing of substantially rectangular cross section to receive said projected light longi- 130

tudinally, a reflecting plate closely fitting longitudinally within the casing and diagonally between opposite side walls thereof, a cover plate, and a plurality of abutments on the rear wall for engagement with one portion of the reflecting plate to prevent its movement in one direction, and means on the reflecting plate engageable by the cover plate at a point diagonally opposite from

the abutments to prevent accidental movement of the reflecting plate in another direction. 10

In testimony whereof I affix my signature in presence of two witnesses.

THOMAS H. WADDEN.
